(No Model.)

E. H. R. HALL
MOCCASIN.

No. 362,507.

Patented May 10, 1887.

UNITED STATES PATENT OFFICE.

ELIZABETH HELEN ROBSON HALL, OF BROCKVILLE, ONTARIO, CANADA.

MOCCASIN.

SPECIFICATION forming part of Letters Patent No. 362,507, dated May 10, 1887.

Application filed February 23, 1887. Serial No. 228,568. (No model.)

To all whom it may concern:

Be it known that I, ELIZABETH HELEN ROBSON HALL, a subject of the Queen of England, residing at Brockville, in the county of 5 Leeds and Province of Ontario, Canada, have invented new and useful Improvements in Moccasins, of which the following is a specification.

My invention relates to improvements in 10 moccasins; and it consists in a certain novel construction and arrangement of parts, fully described hereinafter and claimed.

It is my object to provide a moccasin which 15 will prevent the entrance therein of wet and snow, and which will not sag around the ankle parts when wet, and which will be more readily secured to the foot than the old form.

In the accompanying drawings, Figure 1 is 20 a perspective view of the moccasin. Fig. 2 is a horizontal section through the quarters or ankle parts. Fig. 3 is a central longitudinal section. Fig. 4 is a detached view of the heel-protecting piece. Fig. 5 is a similar view of the bellows-tongue.

25 Referring to the drawings, in which similar letters denote corresponding parts in all the figures, A designates the foot-piece, and B B the quarters or ankle parts, stitched together down the back and along the lower edge to the 30 upper edge of the foot-piece.

C is a canvas, duck, or other suitable stiff lining, placed on the inside of the quarter-pieces and secured thereto by stitching and cement, this latter being designed to aid in excluding the dampness, and also, in addition to the natural stiffness of the lining, to give firmness and strength to the said quarters to prevent the same from sagging when wet.

D represents a piece of stout leather secured 40 by stitching on the inside of the duck lining, at the back of the moccasin and extending the entire height thereof, this piece completely covering the back seam of the moccasin and being a support to the heel thereof. The main object, 45 however, of this strip is to afford a protection to the duck or canvas lining in putting on and taking off the moccasin, this continued wear being apt in time to tear the said lining and deprive the quarters of the necessary stiffness.

50 E E represent narrow strips of stiff leather, which are stitched or otherwise secured on the

inside of the front edges of the quarters, and in perforations formed in said stiffening-strips E and the material of the moccasin are placed the hooked lace-loops F, and riveted therein. To 55 the outer side of the quarters, at points below the lower lace-hooks F, are secured, by rivets or other suitable means, loops f, of leather, through which is passed the lacing cord or thong F'. The use of the said lace-loops is a 60 great improvement over the old manner of securing moccasins, as by this method the quarters can be pulled tightly around the ankle, and the strips E prevent the strain of said pulling from stretching or tearing the material of 65 the moccasin.

G represents the bellows-tongue, formed of the two side strips, g, of very pliable or soft leather, and the central strip or strips, H, of stouter leather, preferably of the same of which 70 the moccasin is made.

In the drawings I have shown two central strips, H, although there may be more or less than two, and the said strips H and g are stitched tightly together, and the outer edges 75 of the side strips are securely attached, by stitching or riveting, or both, to the quarters of the moccasin near the rear edges of the strips E.

When the moccasin is laced, the strips are adapted to close the space between the adjacent edges of the quarters, the quarters lapping over the said tongue, and the side strips, g, are merely designed as a close and pliable connection between the strips H and the quarters, their function being to hold the protecting- 85 strips H in place and prevent snow and dampness, which might work in under the front edges of the quarters, from reaching the interior of the moccasin.

The advantages of my improvement will be 90 evident from the foregoing. The quarters are prevented from sagging, when they become wet, by the stiff lining. The heel is further strengthened and protected from wear by the heel-strip. The lace-loops are adapted to facilitate lacing, and the protecting-strips are placed on the inside of the quarters to prevent stretching and tearing thereof, and a bellows-tongue is placed on the front to exclude all dampness and snow, thus making my improved moccasin a dry, warm, easily-applied, and extremely- 100 durable covering for the foot.

Having thus described my invention, what I claim is—

1. A moccasin having the quarters B and the tongue G, formed of a central stiff section, H, and the leaves g, of pliable leather, permanently secured to the side edges of the central section and to the quarters, substantially as described, for the purpose set forth.
2. A moccasin having the quarters B and a tongue, G, having a central section of stiff leather, and the side sections of pliable leather permanently secured at their inner edges to the central section, the outer edges of the side sections being secured to the inner opposing sides of the quarters B at short distances from the free edges of the latter, to thereby provide flaps which fold or lie over the tongue when the free edges of the quarters are connected together, substantially as described, for the purpose set forth.
3. A moccasin having the quarters B, provided at their free edges with the permanent binding strips E, the lace-hooks secured to the

binding strips, the loops f, secured to the quarters at points below the lower lace-hook, a lace-cord or thong passing through the loops and adapted to engage the lace-hooks, and the tongue having the pliable side sections, g, permanently secured to the quarters in rear of the line of the lace-hooks, to thereby provide flaps which are adapted to fold upon the tongue, as and for the purpose described.

4. A moccasin having the quarters B, a stiffening strip, C, permanently united by cement to the inner side of the quarters at the rear of the same, and the wear-strip D, secured over the stiffening-strip on the inner side of the quarters, substantially as described, for the purpose set forth.

In testimony that I claim the foregoing as my own I have hereto affixed my signature in presence of two witnesses.

ELIZABETH HELEN ROBSON HALL.
